UNITED STATES PATENT OFFICE.

WALTER B. GARRETT AND HARRY M. HOFFMAN, OF CARUTHERSVILLE, MISSOURI.

LOCK-OPERATED CIRCUIT-CLOSER.

1,346,087.

Specification of Letters Patent.

Patented July 6, 1920.

Application filed February 7, 1919. Serial No. 275,627.

To all whom it may concern:

Be it known that we, WALTER B. GARRETT and HARRY M. HOFFMAN, citizens of the United States, residing at Caruthersville, in the county of Pemiscot and State of Missouri, have invented new and useful Improvements in Lock-Operated Circuit-Closers, of which the following is a specification.

10 The object of the invention is to provide a simple apparatus applicable especially to a hotel room door and designed primarily to indicate to the attendants in the hotel that a room is occupied, and that the occupant does not wish to be disturbed. It is a well known fact to those who have frequent occasion to occupy hotel rooms that their work or rest is disturbed by the frequent attempts of the attendants to enter the room for the 15 purpose of cleaning or restoring to condition for further occupancy, and that these attempts are made notwithstanding the fact that the key of the occupant may be in the key hole at the inner side of the door, and it is with a view to giving a positive notice to such attendants that the room is occupied that the present device is designed.

20 A further object of the invention is to provide an apparatus for the purpose indicated which may be applied inconspicuously to a door and under such conditions that it is operative only when the door is closed and the key of the occupant is inserted in the lock from the inside of the door, to the end 25 that attendants may gain access in the ordinary way to the room as in the ordinary practice, when the latter is not occupied or when the occupant has no objection to such entrance.

30 40 Further objects and advantages will appear hereinafter in the course of the following description, it being understood that changes in form, proportion and details may be resorted to within the scope of the appended claims without departing from the 45 spirit of the invention.

In the drawing:

Figure 1 is a view of the door having an attachment embodying the invention applied thereto in the operative position and shown mainly in dotted lines to indicate its location and those of the connections necessary to its effective operation.

50 55 Fig. 2 is an enlarged view of the mechanism proper showing a key in place to close the circuit.

Fig. 3 is a transverse sectional view on the plane indicated by the line 3—3 of Fig. 2.

Fig. 4 is a detail view of the main frame plate adapted to be located beneath the escutcheon plate attached to the door.

Fig. 5 is a detail view of one of the contact plates.

Fig. 6 is a diagram of the circuits.

Fig. 7 is a section on the line 7—7 of Fig. 2.

The device consists essentially of contact plates 10 and 11 which in this instance are shown as slidable members with their terminals mounted in guides 12 which are up-struck from a base plate 13 of such size and proportions as to be arranged beneath the ordinary escutcheon plate of a door lock. These contact plates are yieldingly held in their normal positions by springs 14 which are disposed between ears 15 also preferably up-struck from the base plate and ears 16 up-struck from the contact plates, the tendency of the springs being to move the contact plates inwardly or toward the key hole 70 75 80 17. Connected with binding posts 18 on the contact plates are the conductor wires 19 which may be extended in sealed positions through the panels or frame of the door and terminate in contact buttons 20 for engagement with contact plates 21 in the door frame, these contact plates being in turn 85 90 95 in circuit with service wires or conductors 22. Also in circuit with the contact plates is an incandescent light bulb 23 which may be located in any convenient position on the door as above the lock or handle.

At their inner edges the contact plates are beveled or rounded as shown at 24 and are normally out of contact but in the path 95 of a key inserted through the key hole. As a key is inserted, the apparatus being located under the inside escutcheon of the door, these contact plates are separated, and upon their return due to the action of their springs, they engage the shank of the key and thus complete the circuit which is evidenced by the signal light. Obviously upon the withdrawal of the key the circuit is broken and therefore when the room is unoccupied the apparatus is inoperative. It is customary for a guest in a hotel, after entering his room, to insert the key in the inside of the lock, whether or not he locks the door, and this insertion of the key serves 100 105 110 to close the circuit through the signaling

device and thus give warning at the outside of the door that the room is occupied.

The purpose in constructing the base plate and contact plates of sheet metal, up-struck to form the necessary guiding means and points of contact for the actuating springs is two-fold. In the first place the cost of construction is thereby minimized, and second the device can be made flat and hence suitable for arrangement close to the surface of the door and as above noted beneath the escutcheon plate so that it is invisible and does not in any way affect the general appearance of the door trimming.

15 What is claimed is:—

1. As an article of manufacture a lock-operated circuit closer for hotel doors and the like having a base plate adapted for arrangement under the escutcheon plate of a door lock and having upstruck guides, contact plates slidably mounted in said guides and provided with binding posts for circuit wire connections, said plates forming circuit terminals and being provided with de-

flected key guiding flanges disposed in obstructing relation with the keyhole of the door lock, and yielding means for retaining said contact plates in their normal positions.

2. As an article of manufacture, a lock-operated circuit closer for hotel doors and the like having a base plate adapted for placement under the escutcheon plate of a door and provided with guides, contact plates slidably mounted in the guides and equipped with binding posts for circuit wire connections, said plates forming circuit terminals and having deflected key guiding flanges disposed in obstructing relation with the key hole of the door lock, the base plate and contact plates being formed respectively with upstruck ears, and springs compressed between the ears on the contact plates and the ears on the base plate.

In testimony whereof we affix our signatures.

WALTER B. GARRWELL
HARRY M. HOFFMAN.
